A. T. STEVENTON

HOLDER FOR CIGARETTE LIGHTERS

Filed July 19, 1926

FIG. 1

FIG. 2

FIG. 3

Inventor,
Alfred T. Steventon
by Hubert M. Jenner,
Attorney.

UNITED STATES PATENT OFFICE.

ALFRED THOMAS STEVENTON, OF RICHMOND, ENGLAND.

HOLDER FOR CIGARETTE LIGHTERS.

Application filed July 19, 1926, Serial No. 123,554, and in Great Britain July 31, 1925.

This invention relates to receptacles for cigarettes or cigars, and igniting means therefor, such receptacles being of the kind adapted to be combined with or form part 5 of the handle of a walking stick, umbrella, or riding whip.

According to this invention an open-topped receptacle for cigarettes or cigars is provided in a part of the walking stick or 10 the like near the handle thereof and the part of the stick above the said receptacle is cut through as to form two legs uniting the receptacle and lower part of the stick with the upper part of the stick which is secured 15 to the handle, the said legs being formed on their inner surfaces with grooves in which a lighter such as a petrol lighter is adapted to slide, the said lighter normally fitting tightly over the cigarette receptacle. The 20 lighter may be arranged to tilt to render it readily accessible for use. The top of the receptacle may be stepped or notched to expose parts of the sides as well as the ends of cigarettes therein so that they can readily be 25 picked out between the finger and thumb of the user, and the lighter may carry a scoop-shaped flange which when the lighter is slid down its grooves closes in the stepped or notched part of the receptacle. An 30 external sleeve is adapted to slide longitudinally on the stick so that it can be caused to enclose the receptacle and lighter, and can be slid away from them to expose them when required. Owing to the position of 35 the lighter in a walking stick above the receptacle there is no liability of fumes from the petrol reaching the cigarettes.

In order that the said invention may be clearly understood and readily carried into 40 effect the same will now be described more fully with reference to the accompanying drawings, illustrating an embodiment of this invention, in which:—

Figure 1 is an elevation of a portion of a 45 walking stick having a sliding top which in the position illustrated in this figure closes the receptacle.

Figure 2 is an elevation of the stick with the petrol lighter exposed.

50 Figure 3 is an elevation taken at right angles to that in Figure 2.

A indicates the wooden part of the stick and B a knob at the handle end thereof, which knob may of course be replaced by a crook or other handle of any desired shape 55 and material. A tubular main portion C is preferably secured on a stick A, and may be used as a receptacle for cigarettes. A tubular guide E of the same external diameter as the main portion C is arranged axially in 60 line with the main portion. The parts C and E are rigidly connected to each other by legs H. The lighter D is carried by trunnions d^3 adapted to slide with some little stiffness in grooves h^1 in the inner surfaces 65 of the said legs H. The lid G is formed integrally with the casing of the lighter D or permanently secured thereon; this lid comprises a flange g^2 which when closed covers the stepped part c^1 of the receptacle C and 70 forms a part of the cylindrical wall of the said receptacle. The knob B is provided with a sleeve or tubular extension J having a bayonet slot j^1 engaging a pin K on the part E of the stick so that the sleeve J can be slid down into the position seen in Figure 75 1 to enclose the upper part of the receptacle C, or can be drawn up as seen in Figures 2 and 3 in which latter position the lighter D can be slid on its trunnions d^3 up to the limit 80 allowed by the grooves h^1 thus taking the lid G off the receptacle C, and the said lighter D can then be turned a quarter of a revolution on the said trunnions to bring its head F into a convenient position for use. The part 85 E of the stick being hollowed and notched at e^1 to permit the head F of the lighter to be thus turned out.

Having now described my invention what I claim as new, and desire to secure by Letters Patent is:—

1. The combination, with a tubular main portion, a tubular guide arranged axially in line with the tubular main portion, and longitudinal side members connecting the said main portion and guide, of a lighter pivoted between the said side members, and a sleeve 95 slideable longitudinally on the said guide and main portion and operating to inclose the lighter when same is turned pivotally in one 100 direction.

2. A device as set forth in claim 1, the said

side members having longitudinal slots, and the said lighter having trunnions which slide and pivot in the said slots.

3. A device as set forth in claim 1, the said main portion having a notch on one side, and the said lighter having a flange for closing the said notch in the main portion.

4. A device as set forth in claim 1, the said sleeve having a bayonet slot, and the said guide having a locking pin which is engaged by the bayonet slot. 10

In witness whereof I affix my signature.

ALFRED THOMAS STEVENTON.
